AUTOMATIC GARAGE DOOR OPERATOR

Donato Palumbo, Pueblo, Colo., assignor to
American Automatic Garage Door, Inc., Pueblo,
Colo., a corporation of Colorado

Application June 28, 1938, Serial No. 216,242

5 Claims. (Cl. 268—35)

This invention relates to an automatic garage door operating device and has for its principal object the provision of a simple, mechanical structure, by means of which the weight of an automobile will be employed for automatically opening and closing the garage doors, and for locking the same when the car is in the garage, and to provide means for locking the garage doors as the car leaves the garage without it being necessary for the driver to leave his position in the car.

Other objects and advantages reside in the detail construction of the invention, which is designed for simplicity, economy, and efficiency. 15 These will become more apparent from the following description.

In the following detailed description of the invention reference is had to the accompanying drawings which form a part hereof. Like numerals refer to like parts in all views of the drawings and throughout the description.

In the drawings:

Fig. 1 is a one-half plan view of the automobile driveway into a garage, illustrating a top 25 view of the operating mechanism.

Fig. 2 is a vertical section taken on the line 2—2, Fig. 1.

Fig. 3 is a plan view of the operating mechanism positioned above the garage doors.

30 Fig. 4 is an inside elevation of the mechanism above the doors illustrating the latter in the locked position.

Fig. 5 is an inside view of the door operating mechanism illustrating the doors in the open position.

Fig. 6 is a detail section taken on the line 6—6, 35 Fig. 4.

Fig. 7 is a similar detail section taken on the line 7—7, Fig. 6.

40 Fig. 8 is a similar detail view taken on the line 8—8, Fig. 4.

Fig. 9 is a perspective view illustrating the outside locking mechanism.

45 Fig. 10 is a detail view of one of the operating treads.

Fig. 11 is a plan view of an alternate form of the invention applied to ordinary hinged garage doors.

50 Fig. 12 is an inside elevation of the form of Fig. 11.

Fig. 13 is a detail section taken on the line 13—13, Fig. 11, illustrating the locking means for the alternate form of Figs. 11 and 12.

55 The interior of the garage is designated by the

numeral 10 and the exterior driveway is designated by the numeral 11.

The invention could be used with a single swinging door but it is more particularly designed for use with double swinging doors such as indicated at 12 and 13.

The doors 12 and 13 are mounted upon vertical door shafts 14 and 15, respectively. Each shaft is journaled at the top and bottom of the door and the doors are fixed to the shafts so as to swing therewith. The shafts extend above the doors and terminate in cranks 16.

The cranks 16 of the two doors are connected together above the doors by means of a cross bar 17, the extremities, of which, are pivoted to the cranks in slotted openings 18. At one side of the door opening, a vertical operating shaft 19 is positioned, terminating at its top in an arm 20 which is connected by means of a connecting rod 21 with the cross bar 17. The cranks 16 are faced in opposite directions so that movement of the cross bar 17 will swing the doors in opposite directions.

The operating shaft 19 is journaled at its bottom in a step bearing 22 and adjacent its bottom carries two fixed cross arms 23 and 24. The lower cross arm 23 is connected by means of operating rods 25 and 26 with crank shafts 27 and 28, respectively. The crank shafts are preferably journaled on a foundation plate 31 which can be imbedded or otherwise secured in the driveway. The rods 25 and 26 and the extremities of the crank shafts 27 and 28 are enclosed within a suitable protecting and concealing box 29 alongside of the driveway 11.

Each of the crank shafts forms a part of a treadle. Each treadle consists of two inclined plates 30 hinged at their one extremity to an offset portion in the crank shafts. A leaf spring 32 is secured to the foundation plate 31 and acts to urge the offset portion of the crank shaft upwardly. All of the treadles employed in the invention are of the same construction and all are positioned in the line of travel of the wheels at one side of the automobile. The upper cross arm 24 is connected to a pair of operating rods 33 and 34 which extend to crank shafts 35 and 36 respectively on the interior of the garage. These crank shafts also form part of two interior treadles similar to those previously described. The rods 33 and 34 and the cranks of the crank shafts are concealed in the interior box 37.

The four treadles, for convenience, in description, will be designated A, B, C, and D reading 55

from left to right in Fig. 1. A and D are closing treadles and B and C are opening treadles. It can be readily seen that an automobile approaching the closed garage will first pass its wheels over the closing treadle A and will tend to exert a clockwise direction of rotation to the shaft 19 which will act through the connecting rod 21 to push both doors toward the closed position in which they are already resting.

10 The wheels will then pass over the opening treadle B which will act to rotate the shaft 19 in a counter-clockwise direction to cause the shaft, through the arm 20 and the connecting rod 21, to pull upon the crank 16 to swing both doors to the open position. The car will then enter the garage and its front wheel will pass over the opening treadle C which, being connected to impart a counter-clockwise direction to the shaft 19, will tend to urge the doors open. This wheel will then pass onto the closing treadle D depressing the latter and rotating the shaft 19 to swing the doors to the closed position.

In removing the car from the garage, the front wheel leaves the treadle D and passes onto the treadle C depressing the latter to rotate the shaft 19 counter-clockwise so as to swing the doors open. The wheels then pass over the opening treadle B without effect and onto the closing treadle A to swing the doors to the closed position.

30 Of course, as long as the car's weight remains on the treadle D, it will be impossible for anyone to open the garage doors and the latter are effectively locked.

35 Additional locking means are provided, however, for locking the doors in either the open or closed positions. The additional locking means consist of a notched lock bar 38 which is connected at one extremity to a lever 39 on the operating shaft 19, so that it slides alternately to the left and right as the shaft reciprocates. A latch bolt 40 rides upon the lock bar 38. The latch bolt 40 is suspended from a pivoted member 41 which is constantly urged downwardly by means of a tension spring 42. A notch 43 is formed in the bar 38 adjacent the bolt 40.

When the doors are in the closed position, the notch 43 is below the bolt 40 allowing it to be projected downwardly through a suitable hasp 44 on the inner door 12, thus, securely locking the doors closed. When the door is moved to the open position, the notch is drawn from below the bolt until the latter is raised out of the hasp 44.

50 An arcuate latch member 45 is also secured to the door 12 and rides below a second locking bolt 46. The member 45 is provided with an opening which registers below the bolt 46 when the doors are fully open to lock the latter in this position.

60 A second notch 47 is formed in the bar 38 to allow the bolt 46 to move downwardly under the influence of a spring 48 when the doors are in the fully opened position. Thus, it can be seen the doors may be similarly locked in either the closed or open position so that they cannot be swung closed accidentally.

Means may be provided for locking the doors closed after the car has left the garage. Such a means is illustrated in Fig. 9 in which a perforated locking bar 49 is projected forwardly from the rod 26 through a guide member 50. A key operated lock 51 is supported upon a hollow standard 52 above the slide member 50. This lock, when actuated with a key, acts to raise or lower a locking rod 53 to and from the perfora-

tion in the bar 49. When this rod is in place in one of these perforations, it is impossible to operate the door mechanism.

It is, of course, necessary that the doors be unlocked before they can be either opened or closed. This is provided for by the slotted holes 18 in the cranks 16 which allow the shaft 19 to make a partial rotation, sufficient to withdraw the locking bar 38, before it acts to rotate the cranks 16 thereby allowing a preliminary movement to unlock the latches 40 and 46. The pull rods 25, 26, 33, and 34 are provided with turnbuckles 54 by means of which their lengths can be accurately adjusted to bring the treadles to the proper operating position.

15 The invention is not limited to a door having a door shaft but can be applied to the present hinged doors as shown in Figs. 11, 12, and 13. For this use bracket arms 55 are provided which are secured directly to the doors, shown at 62. 20 These bracket arms are curved so they extend inwardly when the doors are open and each arm is connected by means of a connecting bar 56 with a pivoted equalizing lever 57 which accommodates the opposite movement of the two arms 55. The lever 57 is connected by means of a bar 58 with the crank arm 20 on the operating shaft 19. The operation of the doors is similar to the previously described form.

25 A somewhat different construction in locking devices is shown on the alternate form consisting of a sliding, notched lock bar 59 which is reciprocated by means of a lever 60 and an operating rod 61 from the crank arm 20. The bar operates the latch bolts similarly to the operation of the previously described bar 38.

30 While a specific form of the improvement has been described and illustrated herein, it is desired to be understood that the same may be varied, within the scope of the appended claims, 40 without departing from the spirit of the invention.

Having thus described the invention, what is claimed and desired secured by Letters Patent is:

45 1. Means for operating a pair of swinging doors from the weight of a vehicle comprising: a lever connected with each door; a cross member connecting said levers so that said doors will swing in unison in opposite directions; a vertical shaft adjacent said doors; a crank member on said shaft; a connecting rod attached at its one extremity to said crank member and attached at its other extremity to the middle of said cross member so that rotation of said shaft will swing said doors; and means for rotating said shaft in consequence of the passage of the wheels of a vehicle.

50 2. Means for operating a pair of swinging doors from the weight of a vehicle comprising: a lever connected with each door; a cross member connecting said levers so that said doors will swing in unison in opposite directions; a vertical shaft adjacent said doors; a crank member on said shaft; a connection rod extending from said crank member to a pivot on said cross member intermediate said levers so that rotation of said shaft will swing said doors; a pair of treadles positioned in alignment with each other at each side of said doors; a crank shaft rotated by the 70 depressive movement of each treadle; a cross member on said vertical shaft; connecting rods connecting the treadles of each pair with opposite extremities of said cross member so that when one treadle is depressed, said vertical shaft 75

will be operated to open said doors and when the other treadle of that pair is depressed it will rotate said shaft to close said doors.

3. Means for operating a pair of swinging doors from the weight of a vehicle comprising: a lever connected with each door; a cross member connecting said levers so that said doors will swing in unison in opposite directions; a vertical shaft adjacent said doors; a crank member on said shaft; a connecting rod connecting said crank member with said cross member so that rotation of said shaft will swing said doors; means for rotating said shaft in consequence of the passage of the wheels of a vehicle; a latch bolt 5 for locking said doors in the closed position; and a locking bar operatively connected with said vertical shaft so as to be reciprocated thereby, said bar acting to withdraw said latch bolt prior to the opening operation of said doors.
- 20 4. Means for operating a pair of swinging doors from the weight of a vehicle comprising: a lever connected with each door; a cross member connecting said levers so that said doors will swing in unison in opposite directions; a vertical shaft adjacent said doors; a crank member 25 on said shaft; a connecting rod connecting said crank member with said cross member so that rotation of said shaft will swing said doors; means for rotating said shaft in consequence of the passage of the wheels of a vehicle; a latch bolt 30 for locking said doors in the closed position; a locking bar operatively connected with said vertical shaft so as to be reciprocated thereby, said bar acting to withdraw said latch bolt

prior to the opening operation of said doors; a second latch bolt; means for engaging said second latch bolt when said doors are in the open position; and means on said latch bar for moving said second latch bolt from its locking position prior to the closing of said doors. 5

5. Means for operating a pair of swinging doors from the weight of a vehicle comprising: a lever connected with each door; a cross member connecting said levers so that said doors will swing 10 in unison in opposite directions; a vertical shaft adjacent said doors; a crank member on said shaft; a connection rod extending from said crank member to a pivot on said cross member intermediate said levers so that rotation of said 15 shaft will swing said doors; a pair of treadles positioned in alignment with each other at each side of said door; a crank shaft rotated by the depressive movement of each treadle; a cross member on said vertical shaft; connecting rods 20 connecting the treadles of each pair with opposite extremities of said cross member so that when one treadle is depressed, said vertical shaft will be operated to open said doors and when the other treadle of that pair is depressed it will 25 rotate said shaft to close said doors; a perforated locking bar projecting from the connecting rod that closes the doors; a guide member to receive said locking bar; a hollow standard perpendicularly mounted on said guide member; a locking 30 rod in said standard; a lock carried on the upper extremity of said standard to engage or disengage said locking rod with said perforations.

DONATO PALUMBO.
